UNITED STATES PATENT OFFICE

2,011,300

LIFTING AND PROPULSION DEVICE FOR
USE ON AIR VEHICLES

Otto Karl Quast, Spokane, Wash.

Application April 2, 1934, Serial No. 718,626

3 Claims. (Cl. 170—141)

The general object of the present invention is to provide an apparatus by means of which to elevate heavy loads vertically in a gas and in a fluid medium and to propel the same therein. 5 Another or the main object of the present invention is to apply said apparatus to air vehicles designed to ascend and to descend vertically and also by means of which to hover at will at any desired height and given or chosen point above the ground. 10

With the above and other objects in view, the invention consists in the novel construction, arrangement and formation of parts as will be hereafter more especially described and claimed and which are shown in the accompanying drawing, by which several embodiments of the invention are diagrammatically illustrated by way of example.

Fig. 1 is a general top plan view of said lifting apparatus operating on a horizontal plan; 20

Fig. 2 is a view in section of Fig. 1 taken on line 2—2 thereof;

Fig. 3 is a general top plan view of a modified lifting apparatus of Fig. 1 and is of a multiple construction thereof; 25

Fig. 4 is a view in section of Fig. 3 taken on line 4—4 thereof;

Fig. 5 is a top plan view of a modified lifting apparatus of Fig. 1; 30

Fig. 6 is a view in section of Fig. 5 taken on line 6—6 thereof.

Referring more particularly to the drawing throughout which like reference numerals designate like parts and the elementary functionings involved, the numeral 1 of Fig. 1 indicates a drive shaft entering through the bottom 2 of the stationary receptacle 3 and is held in position and operates in a bearing 4 that is connected to said bottom 2 of said stationary receptacle 3 and a disk plate 5 is held in position and keyed to said drive shaft 1 with blades 6 bolted radially to the upper surface of said disk plate 5, arms or cross bars 7 are connected to said drive shaft 1 and to which said cross bars are hinged hollow globelets 8 or balls 8 by means of flexible cable 9; and the said drive shaft 1, disk plate 5, blades 6, cross bars 7, globelets or balls 8 and flexible cable 9, these make up as a whole the lifting apparatus' rotatable body; and a pipe or air inlet 10 connects the inner space of said receptacle 3 through bottom 2 thereof with the open atmosphere and is controlled by valve 11; a cowling or pressure resisting band 12 encircles at a proper distance the air expeller 13 formed of said disk plate 5 and blades 6, and braces 14 hold said cowling or pressure

resisting band in place by connecting it with the upper rim of said stationary receptacle 3; the numeral 15 indicates a globelet in position when the said rotatable body is at rest, and 16 indicates the gap between the lip 17 of said air expeller 13 from which blades 6 somewhat recede to form said lip 17, and 18 the upper rim of said stationary receptacle 3; and referring to the said elementary functionings involved, when the said air expeller 13 revolves, a column of air is then expelled by said blades 6 centrifugally outward and is spread blanket like by the force of direction of rotation of said air expeller 13, and as this said outflowing and revolving air blanket bridges the said gap 16 between said lip 17 and the said upper rim 18 of said stationary receptacle 3, air is then drawn by it from the inner space of said stationary receptacle 3, forming an area of low pressure therein, and the full atmospheric pressure retained on the upper surface of the said sheet or air blanket in motion will therefore bend the latter to a greater or lesser degree of angle downward, depending on the greater or lesser forces imparted to the outflowing air, and according therewith the said air expeller 13 must be raised 20 or lowered to guarantee a perfect bridging between lip 17 of said air expeller 13 and the upper rim 18 of said stationary receptacle 3; a lowering of said air expeller 13 is called for when air is expelled at a greater velocity, as it will then 25 withstand or counteract the atmospheric pressure from above more readily and will therefore bridge said gap 16 between said air expeller lip 17 and rim 18 of said stationary receptacle 3 on a much straighter line or angle; when the said outflowing air passes over said rim 18 without slightly contacting the latter, air will then rush into receptacle 3 from underneath the said outflowing air blanket and destroy the low pressure therein as created, but on the other hand, when the line 30 of angle of outflow is such that it strikes the inner surface of the wall of said receptacle 3, this also or likewise will destroy the low pressure therein; operating said lifting apparatus Fig. 1, it was found that at the above said perfect bridging between lip 17 and rim 18 a leakage would result regardless of how close the timing of all factors in question, but which was readily overcome when applying the said revolving hinged self-adjustable globelets 8, by their revolving 35 in close contact with said air blanket and the inner surface of said wall of said receptacle 3; it was also found that the atmospheric pressure above the said air blanket when bridging said gap 16 at an angle would here be as great 40 45 50 55

from a lateral direction as that from a straight line above; therefore, it will be understood that by placement of said cowling or pressure resisting band 12, the said lateral pressure is eliminated as proven by its attachment and the resultant increase of lifting capacity of the model on hand; the static atmospheric pressure being equal per square inch under said bottom 2 of said stationary receptacle 3 to that of the upper surface per square inch of said air expeller 13, but which latter is of a smaller area, a greater total atmospheric pressure exerts itself therefore on the lower side of said lifting apparatus and causes it to rise, the energy imparted to the air bridging horizontally said gap 16 it will be seen absorbs the difference, so that therefore when a true bridging by said air of said gap 16 is attained, this we may assume will produce a nearly complete vacuum in said receptacle 3, supplying a great lifting force per square foot area of said gap 16 of said lifting apparatus; operating valve 11, air intake pipe 10, to decrease or to increase the low pressure in receptacle 3 will regulate the ascension and descension of an aircraft provided with said lifting apparatus.

In the construction of lifting apparatus Fig. 3, an outer receptacle 3 of less depth surrounds the inner, or said receptacle 3 of Fig. 1, and cross bars or braces 19 connected to said drive shaft 1 extend outward flush over said rim 18 of said inner receptacle 3, a second or lower air expeller 13 consisting of an annular disk plate 5 and blades 6 connected to said cross bars or arms 19, cross bars 7 connected by braces 20 to said lower air expeller 13 with globelets 8 hinged to said cross bars 7 by said flexible cable 9; in this construction said drive shaft 1, upper disk plate 5 and blades 6 making up the said upper air expeller 13, cross bars or arms 19, annular disk plate 5 and blades 6 making up said lower air expeller 13, and braces 20, cross bars 7, globelets 8, cable 9, all these make up as a whole or as one unit the apparatus' rotatable body; it will be apparent that in this construction the air expelled by the said upper air expeller 13 and bridging said gap 16 of said inner receptacle 3 enters the path of blades 6 of said lower air expeller 13 with energy retained, and further on entering the field of rotation of said lower air expeller encounters less resistance, causing a more effective bridging of said gap 16 of said inner receptacle 3, and causing the air expelled by said lower air expeller to bridge gap 16 of the said outer receptacle more effectively also; thus it will be seen that when carrying the construction of said lifting apparatus into multiplicity that thereby the energy units imparted will be more fully converted into lifting force.

In construction of lifting apparatus Fig. 5, said receptacle 3 is fashioned bowl like and is keyed solidly to said drive shaft 1 and becomes part of the said rotatable body; when this lifting apparatus rotates so that said gap 16 is bridged by air from said air expeller 13, the air contained in said bowl shaped receptacle 3, and the air leaking into it after first exhaustion, is centrifugally forced to said rim 18 to augment and be carried over said rim 18 by the air from air expeller 13; in the former constructions with their stationary

receptacle 3, said air is expelled in like manner, being set in rotation by said rotating air blanket bridging gap 16, by pull of its own weight outward; were it not for the advantages here depicted, a plate inside of said upper rim 18 of receptacle 3 would serve equally as well; when also applying blades 6 to the lower surface of air expeller 13, it was found that said blades would not expedite or increase the low pressure in receptacle 3, which said low pressure is entirely determined by the velocity of the air passing over said gap 16.

Having thus described my invention, it being understood that appropriate changes may be resorted to in its construction without departing from its scope and spirit, what I claim and desire to secure by Letters Patent of the United States is:—

1. A lifting or propulsion apparatus for use in a gas or in a fluid medium comprising a rotatable body having a drive shaft, a disk plate keyed to said drive shaft, blades bolted or attached to the upper surface of said disk plate and radiating from its center and which constitute said apparatus' air expeller, cross bars or arms attached to said drive shaft, a flexible intermediate connecting member attached to said cross bars or arms, hollow globelets or balls attached to said intermediate member, a stationary receptacle with a closed bottom and an open top comprising the stationary base of said lifting or propulsion apparatus, a bearing in the said closed bottom of said stationary receptacle or base fitted through which operates said drive shaft or said rotatable body, braces fitted to the said stationary receptacle or base, a cowling or pressure arresting band attached to said braces, a pressure control air inlet pipe with a control valve connected to the said bottom of said stationary receptacle or base, and the whole operating in a manner creating by a flowing and rotating body of air over a gap of said lifting or propulsion apparatus a low pressure on an area on the upper surface thereof and retaining the full static atmospheric pressure on the lower side thereof intact as its lifting force.

2. Device as claimed in claim 1 comprising an outer stationary receptacle surrounding the first said stationary receptacle, cross bars or arms fitted to said drive shaft, an annular disk plate connected to said cross bars or arms, blades disposed radially and attached to the upper surface of said annular disk plate forming said apparatus' lower or second air expeller, and like in said first construction cross bars, flexible member and globelets disposed and connected by braces fitted to said annular disk plate of last said air expeller.

3. Device as claimed in claim 1 comprising a bowl like receptacle keyed solidly to said drive shaft and forming part of the said rotatable body, and the whole operating in a manner granting that by centrifugal forces, imparted by the inner surface of last said receptacle when in rotation, will expel air therefrom to augment and to expel into free atmosphere with the said air set in motion by said air expeller.

OTTO KARL QUAST.
